TAG-STRINGING MACHINE.

1,351,000.

Specification of Letters Patent. Patented Aug. 24, 1920.

Application filed December 6, 1918. Serial No. 265,605.

To all whom it may concern:

Be it known that I, LAWRENCE A. MCGRATH, a citizen of the United States, residing at Winthrop, county of Suffolk, State 5 of Massachusetts, have invented an Improvement in Tag-Stringing Machines, of which the following description, in connection with the accompanying drawing, is a specification, like characters on the drawing 10 representing like parts.

This invention relates to tag-stringing machines of the general type illustrated in my Patent No. 1,178,932, dated April 11, 1916, and which comprise a threading implement 15 adapted to engage a loop of string and carry said loop through the eye of the tag and around the end of the tag, a loop retainer to receive the loop of the string from the threading implement, and a stringing 20 element adapted to enter the loop and draw the ends of the string therethrough.

The present invention has for its objects to provide an improvement in the manner 25 of handling the string during the stringing operation, a novel means for discharging the tag which may also be used to feed the successive tags of a gang of tags into proper position to be strung, and other improvements, all as will be hereinafter set forth.

30 In order to give an understanding of my invention, I have illustrated in the drawings a selected embodiment thereof which will now be described, after which the novel features will be pointed out in the appended 35 claims.

In the drawings, Figure 1 is a front view of a machine embodying my invention;

Fig. 2 is a side view thereof;

Fig. 3 is an enlarged section on substantially the line 3—3, Fig. 2;

Fig. 4 is a detail of the controlling means for the stringing gripper;

Figs. 5, 6, 7 and 8 are fragmentary views somewhat in the nature of diagrams showing 45 the various steps in the operation of stringing the tag;

Fig. 9 is a plan view of the parts shown in Fig. 7;

Fig. 10 is a plan view of the parts shown in Fig. 8;

50

Fig. 11 is a detail of the devices for operating the rock shaft 44;

Fig. 12 is a detail of the means for operating the thresher;

Fig. 13 is a section on the line 13—13, 55 Fig. 2.

Before describing the machine in detail it will be helpful to refer briefly to the manner in which the tag is strung as illustrated in Figs. 5 to 10 inclusive. The tag to be strung is shown at 1, it being provided with the usual eye 2 through which the string is to be inserted. The length of string with which the tag is to be strung is indicated at 3. The tag is supported in a horizontal position on a supporting table 4 during the stringing operation. The string 3 is inserted through the eye 2 of the tag 1 by means of a threading implement 5 which is herein shown as having a helical shape and 60 which is provided with a notch 6 in one end. The string 3 doubled back on itself is presented to the threading implement 5 by means of a string presenter 7, said presenter 65 carrying the bight in the string 3 into such a position that when the threading implement 5 is rotated about a horizontal axis the notch 6 of said implement will engage the bight of the string and carry it through the eye 2 of the tag and around the end of the tag, as shown in Fig. 6. Situated beneath the tag support 4 is a string-guiding block 8 having a curved under surface 9 which corresponds to the curvature of the threading implement 5. As the string 3 is carried 70 through the eye of the tag and around the end of the tag, it is also passed underneath the curved surface 9 which acts as a string-guiding surface. The threading implement 5 has an oscillatory motion, and when it has 75 completed its forward movement into the position shown in Fig. 6 thereby to carry the loop of the string through the eye and around the end of the tag, said loop is engaged by a loop retainer 10 which moves 80 forwardly to enter the loop of the string.

85

90

95

At this time the threading implement 5 is retracted into its initial position, as shown in Fig. 7, thus leaving the string 3 held by the guiding block 8 and the loop retainer 10.

5 The ends of the string 3 are drawn through the loop held by the loop retainer by means of a pair of stringing grippers 14 which are arranged to enter the loop of string and seize the ends thereof and then 10 to move backwardly to draw the ends through the loop.

The operations as thus far described are substantially the same as set forth in my above-mentioned patent, but in said patent 15 the arrangement is such that only a relatively small portion of the string 3 is inserted through the eye of the tag, the length which is thus inserted being only that necessary to pass around the string-guiding block. As 20 a result, when the stringing grippers 14 enter the loop, they engage the string at a considerable distance from the ends, so that the ends of the string remain in the loop as the grippers move backwardly to tighten 25 the loop, as seen in Fig. 4 of said patent.

My present invention contemplates a construction in which the string is so manipulated that the grippers, while operating close to the tag, will engage the ends of the 30 string, thus avoiding any possibility that said ends will remain in the loop as the latter is tightened. This end is accomplished by means which operates after the loop of string has been inserted through the eye of 35 the tag to draw through said eye the greater portion of the string thereby to bring the ends of the string into a position relatively close to the tag and into position to be seized by the grippers 14.

40 I also preferably employ a string-controlling device situated immediately above the tag when the latter is in stringing position and which is provided with an aperture through which the string is drawn as it is 45 threaded through the eye of the tag, said device operating to apply a tension to the string and also serving to hold the ends of the string in position to be grasped by the grippers. The table 4 is mounted so that 50 it can move vertically and means are provided to lower it after the string has been inserted through the eye of the tag thereby to separate it and the tag from the string-controlling device and thus provide sufficient room for the grippers 14 to operate. By means of this construction a relatively 55 small threader can be employed. The string-controlling device is in the nature of a plate 200 which is situated directly above the table 4 and is provided with an aperture 201 through which the threading implement 5 passes during its threading movement. The loop of string is thus carried through the aperture 201 and through the eye of the tag.

60 65 In drawing the greater portion of the

length of string through the eye of the tag after the threading implement 5 has been retracted, I employ a pull-down 12 which is associated with the block 8 and which normally occupies a notch 13 formed therein 70 so that when the string is passed around the block, as shown in Fig. 6, it is also carried beneath the pull-down. As stated above, the table 4 is lowered into the position shown in Fig. 7 after the string has been threaded through the eye of the tag, and during this movement the pull-down moves downwardly with it. After the table has reached its lowered position shown in Fig. 7, the pull-down has a further downward movement 80 also as shown in Fig. 7, thus operating to draw through the eye of the tag the greater portion of the string so that the ends 15 of the string will be brought about to the string-controlling plate 200. The friction of 85 the string against the walls of the aperture 201 provides sufficient tension to hold the string in its proper position. After the table has been lowered and the pull-down is operated, as shown in Fig. 7, the grippers 14 90 are moved forwardly through the loop held by the loop retainer and between the string-controlling device 200 and the lowered table 4, said grippers operating to seize the ends of the string directly beneath the plate 200. 95 The grippers are then moved backwardly thereby to draw the ends of the string through the loop thereof and because the string is seized immediately at its ends, there is no danger that the ends of the string will 100 be retained in the loop during such backward movement.

Situated beneath the table is a vertically-extending tag-discharging pin 11 which is so positioned that when the table with the 105 tag thereon is lowered into the position shown in Fig. 7, the upper end of the pin will be inserted through the eye of the tag, this occurring after the string has been drawn through said eye. During the backward movement of the grippers 14, the tag-discharging pin 11 is moved laterally, such movement together with the backward movement of the grippers serving to tighten 110 the loop. The lateral movement of the pin 11 also serves to discharge the tag from the table.

The above-described operative parts and the mechanism for actuating them are mounted upon a suitable frame 18, and in the present machine said parts derive their movement from a cam element or elements mounted on a cam shaft 19 which is journaled in said frame and may be driven by any suitable means. I have herein shown 120 said shaft as provided with a belt pulley 20 to receive a driving belt and which may be clutched to or unclutched from the shaft by a suitable clutch (not shown). The threading implement 5 is of the general type 125 130

illustrated in my above-mentioned patent and is operated in a similar manner, it being secured to and carried by a shaft 21 which is journaled in the frame and which is capable of both oscillatory and longitudinal movement. This shaft 21 has a wide-faced pinion 22 fast thereon which meshes with a rack 23 which is mounted for vertical reciprocation in suitable guides 24, such reciprocation of the rack operating to oscillate the shaft 21. Said shaft has a spiral cam rib 25 thereon which operates between two guides 26 so that as the shaft is oscillated, it will be given a longitudinal movement. The pitch of the spiral rib 25 is the same as that of the threading implement 5, and with this arrangement the shaft will be advanced longitudinally as said threading implement passes through the eye of the tag so that the helical shape of the threading implement will not disturb the position of the tag.

The rack 23 derives its reciprocation from a cam groove 26 formed in a cam element 27 mounted on the cam shaft 19, said rack being connected by means of a link 28 to one end of a lever 29 which is pivoted to the frame at 30, said lever having a roll 31 thereon operating in the cam groove 26.

The string presenter 7 which presents a loop of the string 3 to the implement 5 has a construction quite similar to that illustrated in my above-mentioned patent. Said presenter is in the form of a lever or arm 34 having a notched head 32 and pivotally mounted on a stud 33 extending from the frame. Said presenter has an arm 34 rigid therewith which is provided with a pin 35 that engages a face cam 36 mounted on the cam shaft 19, said roll being held against the cam by means of a spring 37 which is connected to the string presenter 7. A length of string is delivered to the string presenter by means similar to that shown in my above-mentioned patent and which comprises a string-measuring arm 38 carried by a shaft 39 which is journaled in the head 40 and is geared to the cam shaft 19 by means of bevel gears 41, said arm in its rotation being adapted to carry a length of string 3 around underneath the notched head 32 of the string presenter, as shown best in Fig. 1. A suitable string-cutting device indicated generally at 42 and similar to that shown in my above-mentioned patent is employed for cutting off from the source of supply a proper length of string at each rotation of the string-measuring arm 38. Since this string-measuring and severing mechanism is similar to that illustrated in my above-mentioned patent and forms no part of the present invention, I have not deemed it necessary to illustrate it and describe it more in detail. It is sufficient to say that at each rotation of the

string-measuring arm 38 a length of string is carried around beneath the notched head 32 of the string presenter, as shown in Fig. 1, and said length is then severed. After the length of string has thus been delivered to the string presenter 7, the cam 36 acts on the arm 34 to depress the presenter into the position shown in dotted lines Fig. 5, thus carrying the bight of the string 3 into position to be engaged by the notch 6 of 75 the threading implement 5.

When the loop of the string has been carried through the eye of the tag and around the end of said tag, as shown in Fig. 6, the loop retainer 10 is moved into the loop of 80 string carried in the notch 6 thereby to retain said loop while the threadder 5 is retracted into the position as stated above, and as shown in Fig. 5. This loop retainer 10 is in the form of an arm pivotally mounted on the stud 33, said arm having an extension 90 provided with a roll 91 which is acted upon by a face cam 92 fast on the cam shaft. A pulling spring 93 holds the roll 91 in engagement with the face cam. This cam is timed to move the loop retainer 10 forwardly at the proper time to cause it to enter and engage the loop of the string and retain said string while the threadder moves back to its initial 95 position and also to cause said loop retainer to be retracted at the proper time in the cycle of operations to drop the loop when the ends 15 of the string are being drawn therethrough.

After the string 3 has been carried through the eye 2 of the tag and around the end thereof, as shown in Fig. 6, the table 4 with the string-guiding block 8 is lowered into the position shown in Fig. 7 thereby to separate 105 the tag from the string-controlling device 200 sufficiently to provide room for the forward movement of the stringing implement 14. To permit this operation said table is carried by an arm 43 which is loosely pivoted 110 on a rock-shaft 44 so that said arm 43 can be moved up and down.

It will be remembered that the guiding block 8 is provided with a recess 13 in which is normally received a pull-down member 12 115 that operates to draw a portion of the string through the eye of a tag. A suitable connection is provided between the arm 43 and the actuating mechanism for this pull-down 12 member 12 so that the movement of the arm 43 is controlled by the pull-down. This pull-down member 12 is in the form of a pin or projection extending laterally from a lever 47 that is fast on the rock-shaft 44. This pull-down arm 47 is pivotally connected by a link 48 120 to an elbow-lever 49 that is pivoted to the frame at 50, one arm of said elbow-lever having the slot 51 therein in which is received a pin 53 carried by an extension 52 extending 125 from and rigid with the arm 43. The slot 51 130

is provided with the portion 54 which is concentric with the pivotal point 50 and is also provided with the cam portion 45 which has an angular relation to the portion 54. When the table is in its elevated position and during the movement of the threader 5, the pin 53 will be in the end of the cam portion 45 of the slot. As the pull-down lever 47 swings downwardly thereby turning the elbow-lever 49, the first or initial downward movement of the elbow-lever operates through the cam portion 45 of the slot to raise the pin 53 and thereby lower the arm 43. When the pin 53 reaches the eccentric portion 54 of the slot, then during further swinging movement of the elbow-lever, the arm 43 will be held stationary. The downward movement of the pull-down lever 47, therefore, operates first to swing the table 4 downwardly into the position shown in Fig. 7, and then to hold the table in this position while the pull-down lever continues its movement.

This downward movement of the arm or lever 47 occurs while the loop or bight of the string 3 is still retained on the loop retainer 10. Such downward movement of the pull-down arm draws the greater portion of the string through the eye of the tag, as shown in Fig. 7, thereby leaving relatively short string ends 15 above the tag. The plate 200 serves to hold such string ends in position to be grasped by the stringing implement 14.

The rock-shaft 44 is actuated from a cam path 80 formed in the face of a cam member 81. This cam path 80 acts on the upper end of a lever 82 pivoted to the frame at 104, the lower end of said lever being connected by a link 84 to an arm 85 fast on the rock-shaft 44. The pull-down arm 47, it will be remembered, is also fast to the rock-shaft, and hence said pull-down arm will receive its movement from the cam path 80 through the connections 82, 84, 85.

45 The stringing grippers 14 which enter the loop of the string 3 while it is retained on the loop retainer 10 and seize the ends 15 of the string and draw said ends through said loop, are carried by a slide 54 which is slidably mounted upon the arm 43. These grippers comprise the two jaws 16 and 17, the jaw 16 being rigid with the slide 54, and the jaw 17 being pivoted to the jaw 16 at 55. The jaw 17 is provided with the rearward extension 56 which is acted upon by a spring 57 that tends to keep the jaws closed. The slide 54 is moved forwardly when the parts are in the position shown in Fig. 7, thereby to carry both jaws through the loop or bight 60 of the string 3 which is retained by the loop retainer 10. The jaws are closed during the first part of the forward movement and until after they have entered the loop. During the final part of their forward movement they 65 are opened to receive the ends 15 of the

string, as seen in Fig. 9, and they are then closed onto the string ends 15, thereby to grip the latter. This opening and closing of the jaws is accomplished by a cam plate 58 which is pivoted at 59 to a plate or support 60 carried by the arm 43 and which is adapted to have engagement with a pin 61 at the end of the arm 56. During the forward movement of the slide 54, said pin 61 will engage the face 62 of the plate 58, and as said pin slides over this inclined face, the jaws will be opened. At the end of the forward movement the pin 61 wipes by the left-hand end of the plate 58 and the spring 57 closes the jaws onto the string ends 15. The slide 54 is then withdrawn into the position shown in Fig. 8 thereby to draw the string ends 15 through the loop of the string 3, and during this backward movement, the pin 61 will engage the face 63 of the plate 58, but because said plate is pivotally mounted it will yield backwardly during the return movement of the grippers, thus preventing the grippers from being opened to release the string. The plate 58 is provided with a stop 90 projection 64 which operates in a slot 65 formed in the plate 60, one end of the slot operating as a stop to prevent the plate from movement during the forward movement of the slide. 95

As the slide 54 is retracted, the pin 61 engages a cam plate 66 thereby opening the jaws 16, 17 to release the string ends.

The cam plate 66 is adjustably sustained on the plate 60 so as to provide for opening the jaws at the desired point in their backward movement. The proper time for releasing the string will depend somewhat upon the size of the tag being strung, and the extent to which it is desired to tighten the loop, etc.

The slide 54 derives its movement from a cam path 100 formed in a cam member 101 fast on the cam-shaft 19. This cam path acts on a follower 102 on the upper end of a lever 103 pivoted to the frame at 104, the lower end of said lever being connected by a link 105 to an arm 106 extending from a rocker or hub 107 that is loosely mounted on the rock shaft 44. Said hub 107 has another arm 108 extending therefrom which is connected to the slide by a link 109. 110

It will be remembered that the lowering movement of the table 4 into the position shown in Fig. 7 causes the tag to be impaled on the pin 11. Means are provided for shifting this pin 11 laterally during the return movement of the grippers 14, and since the strung tag is impaled on the pin, the lateral movement of the pin will carry the tag laterally on the table 4. This lateral movement of the strung tag together with the backward movement of the grippers 14 operates to tighten the loop. 120

The device herein shown is so constructed 130

- that it can be used to string either separate tags or a plurality of connected tags, as shown in dotted lines in Fig. 3, and which are referred to in the trade as gang tags.
- 5 Where the device is used for stringing gang tags, the tag-discharging pin 11 is given a lateral movement in such a direction and of such an amplitude that the operation of carrying the strung tag out of position will
- 10 bring the next succeeding tag of the gang into proper position to be strung. The pin 11 thus operates both as a tag-discharging pin and as a tag-feeding pin.

The table 4 is shown as provided at its rear end with a guiding lip 160 which embraces the edge of the gang tags and guides the latter in their movement over the table. In order that the pin 11 may operate to feed the tags properly, it is necessary that it

20 should have a movement in a right line parallel with the line of feeding movement of the tags. In the construction herein shown, said pin is mounted on the end of an arm 67 which is pivoted on a stud 68 and which has

25 rigid therewith another arm 69 which extends at right angles thereto and is connected by a link 70 to one end of an elbow-lever 71 pivoted to the frame at 72. The other arm of this elbow-lever 71 is connected by a link 73 to a lever 74 that is pivoted to the frame at 75 and is provided with a roll 76 which operates in a cam groove 26. Said cam groove thus performs the double function of actuating the threader and also

30 swinging the arm 67.

In order that the pin 11 may have a right line movement, I propose to make the arm 67 telescopic, it comprising the end section 161 which carries the pin 11 and which telescopes over the portion 162 of the other section. The portion 162 is provided with a pin 163 operating in a slot in the section 161 for the purpose of preventing the outer section from turning on the inner section. The

40 telescopic section 161 is also provided with a vertical pin 164 operating in a groove 165 formed in a block 166 which is detachably secured to the extension 167 of the frame 18. The groove 165 is a straight groove and extends parallel to the line of the gang tags. With this construction it will be apparent that as the arm 67 swings about its pivot 68, the outer end 161 thereof will be moved in a straight line and the tag-discharging pin, therefore, will advance the gang tags in a direction to bring the next unstrung tag into proper position to be strung.

Since tags are made in different sizes it is important that the swinging movement of

50 the pin 11 should be properly adjusted so that it will feed the tags correctly. To provide for this I propose to employ an adjustable connection between the arm 69 and the link 70. The link 70 is shown as forked at its end and the arm 69 is received between

the branches of the fork, said arm being connected to the link by a removable pin 170. The arm 69 is provided with a plurality of apertures 171 into any one of which the pin 170 may be inserted. In this way

70 the effective length of the arm 69 may be adjusted and the pin 11 may be given an amplitude of movement which is just sufficient to correspond to the size of tags being strung.

It will be noted that the pin 11 is not inserted through the eye of the tag until after the string has been drawn through said eye and that the lateral movement of the pin operates to carry the strung tag out of tag-stringing position and into position to be discharged from the platform. Where the tags are in gang formation, this tag-discharging movement of the pin 11 can be made use of to feed the successive unstrung tags into position to be strung, as above described.

When the device is used for stringing individual tags which are separated from each other, then the successive tags will have to

90 be fed into tag-stringing position by hand, but the lateral movement of the pin 11 operates to carry the strung tag out of stringing position and into position to be discharged from the platform. When the separate tags

95 are being strung it is not necessary that the pin 11 should have a right line movement, and if desired, the stand or block 166 may be removed from the support 167 and the two sections of the arm 67 may be clamped together by means of a set screw. In this case the pin 11 would swing in the arc of a circle and the tag would be discharged in the manner shown in Fig. 10. When the pin

100 11 reaches the outer limit of its movement

105 the table 4 is raised thereby to lift the strung tag off from the pin and the pin then returns to a position beneath the tag which is being strung ready to receive said tag when the table is again lowered.

One advantage which is gained by employing the vertically-movable tag-supporting table 4 is that it permits the use of a relatively small threading implement 5 because the vertical movement of the table

110 separates it from the threading implement sufficiently to permit the operation of the stringing element 14.

The machine herein illustrated is compact in structure and is adapted for rapid operation, and while I have illustrated a selected embodiment of my invention, I do not wish to be limited to the constructional features shown.

By the term "string" as herein used, I intend to cover anything in the cord or wire line which might be used for this purpose, and hence the term string is used as illustrative rather than as limiting the use of the apparatus.

I claim:

1. In a tag-stringing machine, the combination with means to insert a loop of string through the eye of a tag and around the edge thereof, of a loop retainer to engage said loop of string, means acting on the string between said loop retainer and tag to draw an added portion of the string through the eye of the tag, and means to draw the ends of the string through the loop thereof. 70
2. In a tag-stringing machine, the combination with means to insert a loop of string through the eye of a tag and around the end thereof, a loop retainer to engage said loop, a pull-down device to act on the string between the tag and the loop retainer and draw an added length of string through the eye of the tag, and means to draw the ends of the string through the loop thereof. 75
3. In a tag-stringing machine, the combination with a block having a curved string-guiding surface, of means to insert a loop of thread through the eye of a tag and around said surface, means to act on the string that passes around said string-guiding surface thereby to draw an added length of string through the eye of the tag, and means to draw the ends of the string through said loop. 80
4. In a tag-stringing machine, the combination with a tag support having associated therewith a curved string-guiding surface, of means to insert a loop of string through the eye of a tag and carry it around said surface, a loop retainer to engage said loop, a pull-down to act on the portion of the string passing around the string-guiding surface thereby to draw an added length of string through the eye of the tag, and means to draw the ends of the string through the loop thereof. 85
5. In a tag-stringing machine, the combination with tag-supporting means comprising a string-guiding member having a notch, of means to insert a loop of string through the eye of a tag and carry it around said string-guiding member, a loop retainer to engage said loop, a pull-down normally occupying said notch, means to actuate the pull-down to draw an added length of string through the eye of the tag, and means to draw the ends of the string through the loop thereof. 90
6. In a tag-stringing machine, the combination with tag-supporting means, of means to insert a loop of string through the eye of the tag, a tag-discharging pin, means to cause said pin to enter the eye of the tag and then to move laterally to discharge the tag from the tag-supporting means, and means to draw the end of the string through the loop thereof. 95
7. In a tag-stringing machine, the combination with tag-supporting means, of means to insert a loop of string through the eye of the tag, a tag-discharging pin, means to cause said pin to enter the eye of the tag and then to move laterally to discharge the tag from the tag-supporting means, and means to draw the end of the string through the loop thereof as the tag is being discharged. 100
8. In a tag-stringing machine, the combination with means for supporting a tag, of means to insert a loop of string through the eye of the tag, a tag-discharging pin, means operating to impale the tag on said pin, means to draw the ends of the string through the loop thereof, and means to move said pin laterally thereby to discharge the tag from the tag-supporting means. 105
9. In a tag-stringing machine, the combination with tag-supporting means, of means to insert a loop of string through the eye of the tag, a pin situated beneath the tag, means to lower the tag-supporting means to cause said tag to be impaled on said pin, means to draw the ends of the string through the loop thereof, and means to move said pin laterally thereby to discharge the tag from the supporting means. 110
10. In a tag-stringing machine, the combination with tag-supporting means, of means to insert a loop of string through the eye of the tag, a tag-discharging pin situated beneath the supporting means and in line with the eye of the tag, means to lower the supporting means to cause said pin to be inserted through the eye of the tag, means to draw the ends of the string through the loop thereof, and means to move the pin laterally. 115
11. In a tag-stringing machine, the combination with tag-supporting means, of means to insert a loop of string through the eye of the tag, a tag-discharging pin situated beneath the supporting means and in line with the eye of the tag, means to lower the supporting means to cause said pin to be inserted through the eye of the tag, means to draw the ends of the string through the loop thereof, and means to give the pin a lateral movement while the ends of the string are being drawn through the loop thereof. 120
12. In a machine for stringing tags, the combination with tag-supporting means, of a threader to carry a loop of string through the eye of the tag, a loop retainer to engage said loop, a pull-down acting on the string between the tag and the loop retainer to draw an added length through the eye of the tag, means to draw the ends of the string through the loop thereof, a cam shaft, and cam mechanism thereon for operating all of said means. 125
13. In a tag-stringing machine, the combination with tag-supporting means, of a threading implement to insert a loop of string through the eye of the tag, a loop retainer to engage said loop, a pull-down acting on the string between the tag and the loop retainer to draw an added length through the eye of the tag, means to draw the ends of the string through the loop thereof, a cam shaft, and cam mechanism thereon for operating all of said means. 130

string through the eye of a tag, means to separate said tag-supporting means and threading implement after a loop of string has been inserted through the eye of the 5 tag, a stringing device, and means to operate it to draw the ends of the string through the loop.

14. In a tag-stringing machine, the combination with a tag-supporting table, of an 10 oscillatory threading implement adapted to insert a loop of string through the eye of a tag and around the end thereof, means to lower the table thereby to separate it from the threading implement after a loop of 15 string has thus been inserted, a stringing device, and means to move it through the loop and into position between the table and threading implement thereby to seize the 20 ends of the string and then to retract it to draw the ends through said loop.

15. In a tag-stringing machine, the combination with a tag-supporting table, of a 25 threading implement to insert a loop of string through the eye of a tag, string controlling means situated between the threading implement and table, and means to draw the ends of the string through said 30 loop.

16. In a tag-stringing machine, the combination with a tag-supporting table, of a 35 threading implement to insert a loop of string through the eye of a tag, means to draw the ends of the string through said loop, and means to apply a tension to the string between the table and the threading 40 implement.

17. In a tag-stringing machine, the combination with a tag-supporting table, of a 45 string through the eye of a tag, means to draw the ends of the string through said loop, and a plate situated between the threading implement and table and having an aperture through which the string is inserted.

18. In a tag-stringing machine, the combination with a tag-supporting table, of a 50 threading implement to insert a loop of string through the eye of a tag, a plate situated between the threading implement and table and having an aperture through which said implement carries the string, means to separate the table from the plate, and stringing grippers adapted to enter the 55 space between the table and plate and seize the ends of the string and draw said ends through the loop.

19. In a tag-stringing machine, the combination with tag-supporting means, of a 60 threading implement to insert a loop of string through the eye of a tag, means to separate said tag-supporting means and threading implement after a loop of string has been inserted through the eye of the 65 tag, means to draw an added length of

string through the eye of the tag, a stringing device, and means to operate it to draw the ends of the string through the loop.

20. In a tag-stringing machine, the combination with tag-supporting means, of 70 means to insert a loop of string through the eye of the tag, a pin situated beneath the tag, means to lower the tag-supporting means to cause said tag to be impaled on the pin, means to draw the ends of the 75 string through the loop thereof, means to move the pin laterally, and means to thereafter elevate the tag-supporting means thereby to free the tag from the pin.

21. In a tag-stringing machine, the combination with tag-supporting means, of 80 means to insert a loop of string through the eye of the tag, a tag-discharging pin, means to cause said pin to enter the eye of the tag after the string has been inserted there-through, means to move the pin laterally to remove the tag from stringing position.

22. In a tag-stringing machine, the combination with tag-supporting means, of 85 means to insert a loop of string through the eye of the tag, a tag-discharging pin, means to cause said pin to enter the eye of the tag after the string has been inserted therethrough, and means to move the pin laterally a distance equal to the width of 90 the tag whereby when gang tags are being strung, the strung tag is removed from stringing position and the next tag brought into position to be strung.

23. In a machine for stringing gang tags, 100 the combination with tag-supporting means, of means to insert a loop of string through the eye of a tag, a combined tag-discharging and feeding pin, means to cause said pin to enter the eye of the strung tag and 105 then to move laterally thereby to remove the strung tag from stringing position and bring the next tag into position to be strung.

24. In a tag-stringing machine, the combination with tag-supporting means, of 110 means to insert a loop of string through the eye of the tag, a tag-discharging pin, means to cause said pin to enter the eye of the strung tag, means for drawing the ends of 115 the string through the loop of string, and means for moving the pin laterally to remove the tag from stringing position, said latter means being adjustable so that the lateral movement may be equal to the width 120 of the tag whereby said pin may be used for feeding gang tags.

25. In a tag-stringing machine, the combination with tag-supporting means, of 125 means to insert a loop of string through the eye of a tag, a pair of stringing grippers, means to carry said grippers through the loop of string and to cause them to seize the ends of the string and then to draw said ends through said loop, thereby stringing 130

the tag, and adjustable means for opening the grippers when the tag is strung.

26. In a tag-stringing machine, the combination with means to insert a loop of string through the eye of a tag, of other means to draw an added length of string through said eye, and means to pass the ends of the string through the loop.

27. In a tag-stringing machine, the combination with means to insert a loop of string through the eye of the tag in two stages, and means to draw the ends of the string through said loop.

In testimony whereof, I have signed my name to this specification.

LAWRENCE A. McGRATH.
